[**] Term: **14 Years**

[57] **CLAIM**

[21] Appl. No.: **64,853**

The ornamental design for an interlocking platform panel for animal confinement pens, as shown and described.

[22] Filed: **Aug. 8, 1979**

DESCRIPTION

[51] Int. Cl. ..... D30—02
 [52] U.S. Cl. D30/2
 [58] Field of Search D30/1, 2; D25/74, 75,
D25/76, 80, 92, 97; 119/28

FIG. 1 is a fragmentary perspective view taken from the top, left side and one end of a interlocking flume platform panel for animal confinement pens embodying my new design;

FIG. 2 is a fragmentary perspective view taken from the bottom, left side and end opposite that shown in FIG. 1;

FIG. 3 is a right side elevational view thereof;

FIG. 4 is a top plan view thereof; and

FIG. 5 is an elevational view of the end shown in FIG. 1.

The flume platform panel has been broken away in FIGS. 1 through 4 to indicate indeterminate length.
